Detroit, Mich.

Application October 11, 1932, Serial No. 637,328

13 Claims. (Cl. 98—29)

The main objects of this invention are to provide a roof structure that will admit light from all directions and provide a uniformly intense illumination over the entire area of a building covered by same; to provide a roof structure that will admit light from all directions and practically eliminate shadows within the entire area of a building covered by the same; to provide a roof structure having bi-directional monitors therein that will efficiently exhaust foul air from a building covered by the same by means of the effect of the difference in temperature of the air inside and outside of the building and the effect of wind blowing from any direction; to provide a roof structure having bi-directional monitors therein that will efficiently exhaust foul air from a building covered by the same by means of the effect of the difference in temperature of the air inside and outside of the building and the effect of wind blowing from any direction; to provide a roof structure having lighting and ventilating means uniformly distributed over the entire roof area; to provide a roof structure having bi-directional uniformly distributed lighting and ventilating means that will permit a building covered by the same to be placed in any direction on any site without reference to prevailing winds or exposure to sunlight and obtain efficient natural light and ventilation therefrom; to provide a roof structure having means for efficient natural light and ventilation in the form of bi-directional monitors at various elevations in respect to the main roof level and at the same time take economic advantage of main cantilever trusses and shallow longitudinal and transverse trusses in supporting the same; to provide a roof structure affording highly efficient natural light and ventilation by means of bi-directional uniformly distributed monitors having sash therein which may be automatically or manually opened and closed as required by directional changes of the wind to maintain leeward sash openings thereby causing continual and efficient exhausting of foul air from a building so covered.

Other objects and advantages of our invention will become apparent by reference to the following detailed description and accompanying drawings, in which:—

Fig. 1 is a plan view of the roof of a building indicating one embodiment of our invention showing the general arrangement of monitors.

Fig. 2 is a plan view of the roof of a building indicating another embodiment of our invention showing the general arrangement of monitors on a relatively narrow building.

Fig. 3 indicates various wind directions for the

purpose of defining the operation of monitor and side wall sash in Fig. 1 and Fig. 2.

Fig. 4 is a sectional perspective taken on line 4—4 of Fig. 1.

Fig. 5 is a sectional perspective taken on line 5—5 of Fig. 2.

Fig. 6 is a section taken on lines 6—6 of Fig. 1 and Fig. 9 looking in the direction indicated by the arrows.

Fig. 7 is a section taken on lines 7—7 of Fig. 1 and Fig. 9 looking in the direction indicated by the arrows.

Fig. 8 is a section taken on lines 8—8 of Fig. 1, Fig. 2 and Fig. 9 looking in the direction indicated by the arrows.

Fig. 9 is a plan view of the roof of a building indicating still another embodiment of our invention showing the general arrangement of monitors on a relatively wide building.

Fig. 10 indicates various wind directions for the purpose of defining the operation of monitor and side wall sash in Fig. 9.

In the construction shown in Fig. 1, Fig. 4, Fig. 6, Fig. 7 and Fig. 8 a building is provided with a roof 11 which may be bounded on all sides with the usual parapet walls 12. Groups of continuous U-shaped monitors 13 are generally distributed over the entire area of the building. The roofs 14 of the continuous U-shaped monitors 13 are vertically spaced above the general roof level 11 at such a distance that permits the use of vertical sash 15 on all sides of the said continuous U-shaped monitors 13. Intermediate monitors or A-frames 16 are spaced between the transverse portions of the continuous U-shaped monitors 13. The roofs 17 of the monitors or A-frames 16 are vertically spaced above the general roof level 11 at a lesser height than the continuous U-shaped monitor roofs 14. Sash 18 is provided in the sides of the monitors or A-frames 16, the said sash 18 being preferably of a fixed type. A main longitudinal monitor 19 is spaced between the ends of the groups of continuous U-shaped monitors 13. The roof 20 of the main longitudinal monitor 19 is vertically spaced above the general roof level 11 at such a distance that permits the use of vertical sash 21 on the side thereof.

The said roof 20 of the main longitudinal monitor 19 is at a relatively higher level than the continuous U-shaped monitor roofs 14. The vertical sash 15 of the continuous U-shaped monitors 13 and the vertical sash 21 of the main longitudinal monitor 19 contain pivotal units 22 which may be opened or closed as hereinafter specified. The building upon which the roof is constructed is 55

enclosed by means of the usual walls 23 and the usual side wall sash 24 containing pivotal units which may be opened or closed as hereinafter specified.

5 Fig. 6 and Fig. 7 are transverse sections showing one half of the building indicated in Fig. 1 and Fig. 4, the said building being symmetrical about the line 25 in Fig. 6 and the line 26 in Fig. 7. The main transverse cantilever trusses are 10 supported on interior columns 28. The center transverse trusses 29 are supported by the cantilever ends 30 of the cantilever trusses 27. The side transverse trusses 31 are supported by the cantilever ends 32 of the cantilever trusses 27 and 15 at the wall the said side transverse trusses 31 are supported on the wall columns 33.

High longitudinal trusses 34 support the roofs 14 of the continuous U-shaped monitors 13. Low longitudinal trusses 35 support the low roof 11 20 and the intermediate monitors or A-frames 16. Low longitudinal trusses 36 support the low roof 11 and the main longitudinal monitor 19. Low longitudinal trusses 37 support the side band of 25 low roof 11 between the outside wall of the continuous U-shaped monitor 13 and the parapet wall 12. Main transverse cantilever trusses 27, and high longitudinal trusses 34 serve as monitor wall framing in addition to carrying their respective roof and monitor roof loads.

30 The entire system of continuous transverse trusses 27, 29, and 31 in addition to supporting their share of the roof and monitors serve as a system of transverse bracing. The entire system of longitudinal trusses 34, 35, 36, and 37 in addition to supporting their share of the roof and monitors serve as a system of longitudinal bracing. Though but one system of roof framing has been shown and described, arrangement and detail thereof may be altered to suit special conditions without departing from the spirit of this 40 invention.

Fig. 2 and Fig. 5 indicate another embodiment of our invention applied to a relatively narrow building in which the roof 11 may be 45 bounded on all sides with the usual parapet wall 12. A continuous S-shaped monitor 38 is generally distributed over the entire area of the building. The roof 14 of the continuous S-shaped monitor 38 is vertically spaced above the 50 general roof level 11 at such a distance that permits the use of vertical sash 15 on all sides of the said continuous S-shaped monitor 38. Intermediate monitors or A-frames 16 are provided between the transverse portions of the continuous S-shaped monitor 38. The roofs 17 of the intermediate monitors or A-frames 16 are vertically spaced above the general roof level 11 at a lesser height than the continuous S-shaped monitor roof 14. Sash 18 is provided in the sides of the 55 monitors or A-frames 16, the said sash 18 being preferably of a fixed type. The vertical sash 15 of the continuous S-shaped monitor 38 contains pivotal units 22 which may be opened or closed as hereinafter specified. The building upon which the roof is constructed is enclosed by means of the usual walls 23 and the usual sidewall sash 24 containing pivotal units 22 which may be opened or closed as hereinafter specified. The structural features of this embodiment of our invention are 60 typical with the construction shown in Fig. 6, Fig. 7 and Fig. 8 as may be noted by referring to Fig. 2 and Fig. 5.

Fig. 9 indicates still another embodiment of our invention applied to a relatively wide building in which the roof 11 may be bounded on all 75

sides with the usual parapet wall 12. Groups of continuous U-shaped monitors 13 are generally distributed along each side of the building. The roofs 14 of the continuous U-shaped monitors 13 are vertically spaced above the general roof level 5 11 at such a distance that permits the use of vertical sash 15 on all sides of the said continuous U-shaped monitors 13. Intermediate monitors or A-frames 16 are spaced between the continuous U-shaped monitors 13. The roofs 17 of the 10 monitors or A-frames 16 are vertically spaced above the general roof level 11 at a lesser height than the continuous U-shaped monitor roofs 14. Sash 18 is provided in the sides of the monitors or A-frames 16, the said sash 18 being preferably 15 of a fixed type. A main longitudinal monitor 19 is located in spaced relation to the ends of each of the two groups of continuous U-shaped monitors 13. The roofs 20 of the main longitudinal monitors 19 are vertically spaced above the general roof level 11 at such a height that permits the use of vertical sash 21 on the sides thereof. The said roofs 20 of the main longitudinal monitors 19 are at a relative higher level than the continuous U-shaped monitor roofs 14. In the central portion of the building a plurality of transverse rectangular monitors 39 are located in spaced relation to the transverse portions of the continuous U-shaped monitors 13 and between the two main longitudinal monitors 19. The 25 rectangular monitors 39 are identical in detail with the transverse portion of the continuous U-shaped monitors 13. Intermediate monitors or A-frames 40 are spaced between the transverse monitors 39 and are identical in detail with the 30 intermediate monitors or A-frames 16. The vertical sash 15 of the continuous U-shaped monitors 13, the vertical sash 15 of the transverse rectangular monitors 39 and the vertical sash 21 of longitudinal monitors 19 contain pivotal units 40 22 which may be opened and closed, as herein-after specified. The building upon which the roof is constructed is enclosed by means of the usual walls 23 and the usual sidewall sash 24 containing pivotal units 22 which may be opened or 45 closed as hereinafter specified. The structural features of this embodiment of our invention are typical with the construction shown in Fig. 6, Fig. 7, and Fig. 8 as may be noted by referring to Fig. 9. 50

It is to be understood that where continuous U-shaped or continuous S-shaped monitors have been specified that the continuity of the U or S may be broken so that a series of U-shaped monitors or a series of S-shaped or a series of L-shaped monitors may be substituted or that the size and/or height of the monitors or portions of monitors may be varied to suit special conditions without departing from the spirit of our invention. 55

Roof drainage is provided through interior 60 catch basins 41 and exterior catch basins 42 down drain pipes 43 and thence to the usual sewer connection. The roof structure is so sloped that water on the roof will flow to the catch basins 42 and 43, the number and location of which are 65 optional and vary according to specific requirements.

To describe the operation of the pivotal units 22 of monitor sash 15, monitor sash 21 and side wall sash 24 it must be understood that to obtain efficient natural ventilation openings must be provided on the leeward side of monitors or walls in the upper part of the structure to exhaust foul air and in the side walls on the windward side in the lower part of the structure to permit the en- 70 75

trance of fresh air; also openings in the lower portion of the side wall on the leeward side may act as fresh air inlets under certain weather conditions. At such times as there is little or no wind action it is desirable to provide a maximum of openings both in the monitors and in the lower portions of the side walls.

The operation of the said pivotal units 22 of monitor sash 15, monitor sash 21, and side wall sash 24, may be performed either by automatic or manual means or by any combination of automatic and manual means.

Referring to Fig. 1, Fig. 2, and Fig. 9 various groups of pivotal units have been indicated by dotted lines. Numerals 47, 48, 49, and 50 designate groups of pivotal units 22 in monitor sash 15; numerals 51 and 52 designate groups of pivotal units 22 in monitor sash 21, and the numerals 53, 54, 55, and 56 designate groups of pivotal units 22 in side wall sash 24.

Referring now to Fig. 1 and Fig. 3 and assuming that the direction of the wind is as indicated by the arrow 44 of Fig. 3 then the groups of pivotal units 47, 48, 50, and 51 are closed and groups of pivotal units 49, 52, 53, 55, are opened. Groups of pivotal units 54 and 56 are preferably opened but may be partially or totally closed according to weather conditions.

Again referring to Fig. 1 and Fig. 3 and assuming that the direction of the wind is as indicated by the arrow 45 of Fig. 3 then the groups of pivotal units 47, 48, and 51 are closed and groups of pivotal units 49, 50, 52, 53, 54, 55, and 56 are opened.

Still again referring to Fig. 1 and Fig. 3 and assuming that the direction of the wind is as indicated by the arrow 46 of Fig. 3 then the pivotal units 47, 48, 49, 51 and 52 are closed and groups of pivotal units 50, 54, and 56 are opened. Groups of pivotal units 53 and 55 are preferably opened but may be partially or totally closed according to weather conditions.

Operation has been defined for wind directions 44, 45, and 46 within one quadrant of the compass, operation when the wind direction is in the other quadrants of the compass is apparent by analogy.

When the velocity of the wind drops below a certain predetermined point, for example 5 miles per hour, which may be varied according to the season of the year and according to temperature, then all groups of pivotal units may be opened totally or partially and ventilation is obtained by means of the effect of the difference in temperature of the air inside and outside the building, commonly termed "stack action".

The operating of the groups of pivotal units 47 to 56 inclusive in the embodiment of our invention shown in Fig. 2 is identical to the operation described for the embodiment shown in Fig. 1. The operation of the groups of pivotal units 47 to 56 inclusive shown in Fig. 9 is identical to the operation described for the embodiment shown in Fig. 1, the various wind directions being indicated in Fig. 10 for convenience. Like reference numerals designate similar parts throughout the several views.

Although but a typical method of operation of the groups of pivotal units has been described it is to be understood that special conditions may require a variation in the groupings of the pivotal units and their sequence of operation and that such special conditions may be provided for without departing from the spirit of this invention.

In practice it has been usual to locate manufacturing plants and other structures on their site with special reference to prevailing winds

and direction of sunlight which often required expensive construction, undesirable arrangement of operations within the structures and complicated layout of railroad tracks and driveways to obtain full advantage of natural light and ventilation. Buildings oriented to take advantage of prevailing winds for ventilation are inefficient in ventilation when wind is from other directions than the prevailing one. If it were impossible to properly locate manufacturing plants or other structures with reference to prevailing winds and direction of sunlight due to the size of the plant, availability of railroad connections, operations within the structures, and the shape of the property, the project would require expensive construction to embody in the structures the necessary facilities to provide proper natural light and ventilation, or proper natural light and ventilation would be omitted resulting in either continuous expense in power ventilation and artificial lighting or undesirable working conditions.

Our invention is a distinct advancement in the art of roof structures in that we provide means for proper natural lighting and highly efficient ventilating through controlled monitor and side-wall sash openings which may be applied to any structure without inconvenient arrangement or expensive special construction to suit the conditions of prevailing winds and the direction of sunlight; and in addition to utilizing the full value of the prevailing winds to provide natural ventilation our invention provides equally efficient natural ventilation with winds from any and varying directions. Also in our invention light is admitted from all directions which practically eliminates undesirable shadows. The above and all other advantages that may be obtained from the use of our invention is accomplished without great expense in that the supporting structure of the roof and generally distributed monitors serves a treble purpose; supporting the roof, bracing the building and in providing wall framing for a large proportion of the monitors.

Although but one specific embodiment and two modifications of this invention have been herein shown and described, it is to be understood that numerous details of construction may be altered or omitted without departing from the spirit of this invention as defined by the following claims.

We claim:—

1. A roof structure comprising a main roof, two continuous U-shaped monitors, intermediate monitors spaced between the transverse portions of the said continuous U-shaped monitors, and a main longitudinal monitor spaced between the two continuous U-shaped monitors.

2. A roof structure comprising a main roof, longitudinally disposed continuous U-shaped monitors, transversely disposed intermediate monitors spaced between the transverse portions of the said continuous U-shaped monitors and a main longitudinal monitor spaced between the continuous U-shaped monitors.

3. A roof structure comprising a main roof, longitudinally disposed continuous U-shaped monitors, transversely disposed intermediate monitors spaced between the transverse portions of the said continuous U-shaped monitors, a main longitudinal monitor spaced between the said continuous U-shaped monitors, the said monitors being vertically disposed at a plurality of distances above the said main roof.

4. A roof structure comprising a main roof, a continuous S-shaped monitor and intermediate

monitors spaced between the transverse portions of the said continuous S-shaped monitor.

5. A roof structure comprising a main roof, a longitudinally disposed continuous S-shaped monitor and intermediate monitors spaced between the transverse portions of the said continuous S-shaped monitors, the said monitors being vertically disposed at a plurality of distances above the said main roof.

10 6. A roof structure comprising a main roof and a series of monitors uniformly distributed over the main roof, the said series of monitors comprising a continuous U-shaped monitor along each side of the said roof structure, a plurality 15 of transverse rectangular monitors along the center of the said roof structure located in spaced relation to the transverse portions of the said continuous U-shaped monitors, intermediate transverse monitors spaced between the transverse 20 portions of the said continuous U-shaped monitors, intermediate transverse monitors spaced between the transverse rectangular monitors and longitudinal monitors spaced between the transverse 25 ends of the continuous U-shaped monitors and the ends of the transverse rectangular monitors.

7. A roof structure comprising a main roof and a series of monitors uniformly distributed over the main roof, the said series of monitors comprising a continuous U-shaped monitor along each side of the said roof structure, a plurality of transverse rectangular monitors along the center of the said roof structure located in spaced relation to the transverse portions of the said continuous U-shaped monitors, intermediate transverse monitors spaced between the transverse portions of the said continuous U-shaped monitors, intermediate transverse monitors spaced between the transverse rectangular monitors and longitudinal monitors spaced between the transverse 30 ends of the continuous U-shaped monitors, the said monitors being vertically disposed at a plurality of distances above the main roof.

40 8. A roof structure comprising a main roof, a series of bi-directional monitors uniformly distributed thereon said monitors extending longitudinally in a plurality of directions, a series of cantilever transverse trusses and longitudinal trusses supporting and bracing the said main and monitor roofs, the roofs of the said monitors spaced at a plurality of distances above the main roof, monitor walls between the main and monitor roofs, sash in the said monitor walls and piv-

otal ventilating units in the said sash capable of being operated manually or automatically according to the direction of passing air currents and various weather conditions.

5 9. A roof structure comprising a substantially level main roof, longitudinally disposed continuous U-shaped monitors, transversely disposed intermediate monitors spaced between the transverse portions of the said continuous U-shaped monitors, a main longitudinal monitor spaced between the said continuous U-shaped monitors, the said monitors being vertically disposed at a plurality of distances above the said main roof.

10 10. A roof structure comprising a substantially level main roof, a longitudinally disposed continuous S-shaped monitor and intermediate monitors spaced between the transverse portions of the said continuous S-shaped monitors, the said monitors being vertically disposed at a plurality of distances above the said main roof.

15 11. A roof structure comprising a substantially level main roof and a series of monitors uniformly distributed over the main roof, the said series of monitors comprising a continuous U-shaped monitor along each side of the said roof structure, a plurality of transverse rectangular monitors along the center of the said roof structure located in spaced relation to the transverse portions of the said continuous U-shaped monitors, intermediate transverse monitors spaced between the transverse rectangular monitors and longitudinal monitors spaced between the transverse 20 ends of the continuous U-shaped monitors and the ends of the transverse rectangular monitors.

25 12. A roof structure comprising a substantially level main roof, a monitor extending longitudinally in a plurality of directions thereon, and intermediate monitors spaced between portions of the monitor, said monitors having roofs spaced at different elevations above the main roof.

30 13. A roof structure comprising a substantially level main roof, a plurality of multi-directional monitors distributed thereon, intermediate monitors spaced between portions of the multi-directional monitors, and a rectangular monitor spaced between the said multi-directional monitors, said monitors having roofs spaced at different elevations above the main roof.
